UNITED STATES PATENT OFFICE.

LORENZO C. DENSLOW, OF FALLS CHURCH, VIRGINIA.

SPRING JACK.

Application filed March 1, 1924. Serial No. 696,231.

To all whom it may concern:

Be it known that I, LORENZO C. DENSLOW, a citizen of the United States, residing at Falls Church, in the county of Arlington and State of Virginia, have invented certain new and useful Improvements in Spring Jacks, of which the following is a specification.

This invention relates to an improved 10 spring jack and while being well adapted for general application is more particularly designed for use in radio work.

The invention seeks, among objects, to provide a jack which will effect an economy 15 in the depth of space occupied by the jack, so as to permit more compact assembling of radio sets.

The invention seeks, as a further object, to provide a jack involving a novel arrangement of the spring contacts employed so that said contacts will be readily accessible for the connection of circuit wires thereto, while the possibility of current leakage or 20 short circuiting between the contacts will be effectually avoided.

And the invention seeks, as a still further object, to provide a jack which will be of extremely simple construction to the end that the device may be manufactured and 25 sold at moderate cost.

Other and incidental objects will appear hereinafter.

In the drawings:

Figure 1 is a perspective view showing a 30 single circuit jack embodying the present invention,

Figure 2 is a longitudinal sectional view through the jack, and showing a conventional plug inserted therein,

Figure 3 is a perspective view showing a 40 double circuit jack constructed in accordance with the invention, and

Figure 4 is a sectional view showing a further modification of the invention.

In so far as I am aware, spring jacks heretofore used in radio work have all been of the type commonly employed in the telephonic art, the usual jack of a typical telephone switch board simply being borrowed, so to speak, and pressed into service in building radio sending and receiving sets. While being entirely efficient for its intended purpose, the usual telephone jack is, however, subject to many disadvantages 50 in the new environment of a radio set. Owing to the proximity of other parts, dif-

ficulty is often experienced in reaching the connector lugs of the spring contacts for the attachment of wires thereto. Furthermore, these lugs are very close together, 60 rendering it extremely difficult for the amateur to properly secure the wires. Also, the insulation between the contacts often becomes impaired, under inexperienced handling of the jack, with the result that 65 the set of the amateur, when finished, contains a hidden fault in the jack and, in this connection, it may also be noted that, when soldering paste is allowed to flow, during 70 a soldering operation, onto the insulation of the usual telephone jack, the paste tends to collect about the insulation with the result that current leakage often ensues while the finished set is rendered noisy by the 75 corrosive action of the paste. Another disadvantage of the usual telephone jack lies in the fact that such a jack, when mounted on the panel of a radio set, projects a considerable distance at the back of the panel and thus occupies an unwarranted depth, 80 necessitating the spacing of other instruments of the set rearwardly from the panel or resorting to the expedient of a shelf. The present invention, therefore, seeks to provide a jack which will overcome the 85 various disadvantages noted and which will be especially adapted to the peculiarities of radio installation.

Referring now more particularly to Figures 1 and 2 of the drawings, I have illustrated a single circuit jack embodying the present invention. A base 10 of suitable insulating material is employed and formed through the base is a medial plug opening 11. The base is flat, so that, as suggested in Figure 2, the base may be rested against a panel, as conventionally illustrated at 12, and formed through the base are appropriately located openings 13 to receive screws or other suitable fastening devices 14 90 securing the base to the panel, the panel being provided, of course, with an opening to register with the opening 11 of the case. Inserted through the base near the ends thereof are binding posts 14 alining with the plug opening 11 and mounted upon the binding posts are spring contacts indicated for convenience at 15 and 16. These contacts are provided with slots 17 to freely receive the posts 14 so that said contacts 100 may be readily adjusted with respect to the opening 11 and securing the contacts in ad-

justed position are nuts 17' screwed upon the posts. Preferably, the posts also carry thumb nuts 18 so that circuit wires may be readily secured to the posts.

5 The spring contacts 15 and 16 extend toward the plug opening 11 in radial relation to the axis thereof and are bent near their outer ends to diverge or incline away from the base while at points medially thereof 10 said contacts are again bent so that the free end portions of the contacts lie in approximately parallel relation. In other words, the contacts are offset so that the contacts stand away from the base throughout the 15 major portion of their length while the free end portions of the contacts approach parallelism and, as will now be observed, the contact 16 is offset at a greater angle than the contact 15 so that the free end of the former 20 contact overhangs the free end of the latter contact in spaced relation. At their free ends, the contacts are turned laterally away from the base to form rounded contact lips 19 and 20 and, as will now be observed, the 25 contact 15 is of such length that the lip 19 thereof does not quite touch the axis of the plug opening 11 while the contact 16 is longer than the contact 15 so that the free end of the contact 16 extends across said 30 opening.

As will now be seen in view of the foregoing when a plug, as conventionally illustrated at 21, is inserted through the panel 12 and through the plug opening 11 of the base 35 10, the tip of the plug will first strike the lip 19 of the contact 15 for deflecting the free end of said contact, when the contact will be flexed away from the base and thus brought under tension to bear against the 40 side of the plug shank. As the plug is then advanced, the tip of the plug will next strike the lip 20 of the contact 16 when, in like manner, the free end of the contact 16 will be deflected and said contact flexed away 45 from the base and accordingly brought under tension against the side of the tip. As will be noted, the contact 16 is of such length that when the plug has reached the limit of its inward movement, the lip 20 of said contact will seat in the groove at the base of the tip so that the plug will thus be yieldably gripped between the contacts while the lip 50 20 of the contact 16 will cooperate with the tip for holding the plug against accidental 55 retraction. In this connection it is to be observed that due to the acuteness of the angles between the base and the free ends of the contacts, initial retractive movement of the plug will slightly drag said ends of the contacts toward the base and tend to wedge the plug between the contacts so that the plug 60 will thus be locked against accidental endwise displacement. Efficient and proper electrical connection between the contacts 65 and the plug will thus be maintained. By

adjusting the contacts upon the posts 14, the contacts may be positioned to properly cooperate with plugs of different length and likewise, compensation may be readily made for variation in the thickness of different panels. 70 When the plug is inserted or removed, the plug will, of course, shift across the lips 19 and 20 of the contacts, so that the incident wear on said lips will maintain the lips bright and clean. Furthermore, the binding 75 posts 14 are, comparatively speaking, widely separated, so that circuit wires may be readily connected to said posts and since the contacts are arranged in radial relation to the plug opening of the base instead of parallel to the axis of said opening, as in the usual jack, the device is rendered compact and will occupy but very little depth at the back of the panel.

In Figure 3 of the drawings, I have illustrated a slight modification of the invention embodying a double circuit jack. In this modification, I employ a base 22 of suitable insulating material and formed in the base is a plug opening 23 in juxtaposition to 85 which are arranged spring contacts 24 and 25, as in the prior embodiment, said contacts being mounted on binding posts 26. Resting flat against the base to extend transversely beneath the free ends of the contacts 24 and 95 25 are cooperating contacts 27 and 28 secured near corresponding ends thereof by binding posts 29 similar to the binding posts 26 and near their opposite corresponding ends by screws 30. At the latter ends thereof, these contacts are formed with upstanding contact lugs 31 and 32 normally seating the contacts 24 and 25, the lug 32 being somewhat longer than the lug 31. Thus, under ordinary circumstances, a circuit will be 100 closed through the contacts 24 and 27 and through the contacts 25 and 28. However, when the plug is inserted through the plug opening 23 to engage the free ends of the contacts 24 and 25, these contacts will be 105 lifted away from the contact lugs 31 and 32 while the contacts 24 and 25 will cooperate with the plug to complete a circuit there-through. This modified structure thus also provides a very efficient device and, as will 110 be seen, the advantages incident to the preferred form of the invention are also resi- 115 dent in the modified structure.

In Figure 4 of the drawings, I have illustrated a further modified structure wherein 120 I employ a base 33 having a plug opening 34 and mounted upon the base to extend toward said opening, as in the preferred form of the invention, is a spring contact 35 adjustably secured by a binding post 36. 125 Extending beneath the free end portion of the contact 35 is a second contact 37 adjustably mounted by a binding post 38 and provided at its free end with an upturned lug 39 to cooperate with the contact 35. Ar- 130

ranged to extend over the contact 35 is a third contact 40 adjustably mounted by a binding post 41 and provided at its free end with a downturned lug 42 for engagement by the contact 35. Thus, under ordinary circumstances, the contact 35 will seat against the lug 39 of the contact 37 for closing a circuit through said contacts. However, when a plug is inserted through the opening 34, the contact 35 will be lifted out of engagement with the lug 39 of the contact 37 and shifted into engagement with the lug 42 of the contact 40 for closing a circuit through the contacts 35 and 40 while, at the same time, the contact 35 will, of course, make connection with the plug.

Having thus described the invention, what I claim is:

1. A spring jack including a base provided with an opening, spring contacts mounted upon the base at one side thereof and inclining away from said side of the base to impinge at their free ends against a plug inserted through said opening, and means connecting the contacts with the base for adjustment to vary the effective length of said contacts.

2. A spring jack including a base provided with an opening, spring contacts mounted upon the base at one side thereof and inclining away from said side of the base to impinge at their free ends against a plug inserted through said opening, said contacts being provided with slots, and means extending through said slots connecting the contacts with the base, the contacts being adjustable upon said means for varying the effective length of said contacts.

3. As a new article of manufacture, a spring jack including, in combination, a separate individual base provided with an opening, and spring contacts mounted upon and inclining away from the base each at an angle less than forty-five degrees, said contacts being bent medially to define angularly disposed free ends extending in substantially parallel relation to impinge at

their free terminals against a plug inserted through said opening whereby initial retractive movement of the plug will slightly drag the free ends of the contacts toward the base and tend to wedge the plug therebetween for locking said plug against accidental displacement.

4. A spring jack including a base provided with an opening, and spring contacts mounted upon and inclining away from the base, one of said contacts extending at a less angle to the base than the other but each extending at an angle less than forty-five degrees and both of said contacts being bent medially to define angularly disposed free ends extending in substantially parallel relation to impinge at their free terminals against a plug inserted through said opening whereby initial retractive movement of the plug will slightly drag the free ends of the contacts toward the base and tend to wedge the plug therebetween for locking said plug against accidental displacement.

5. A spring jack including a base having an opening, a contact carried by the base, and another contact inclining away from the base over the former contact to normally engage therewith and having its free end disposed to impinge a side of a plug inserted through said opening, the latter contact being movable by the plug away from the base out of engagement with the former contact.

6. A spring jack including a base having an opening, contacts carried by the base, and other contacts inclining away from the base at unequal angles over said first mentioned contacts to normally engage therewith and having their free ends staggered and disposed to impinge the sides of a plug inserted through said opening, the latter contacts being movable by the plug away from the base out of engagement with said first mentioned contacts.

In testimony whereof I affix my signature.
LORENZO C. DENSLAW. [l.s.]
